Primary Examiner — Darlington Ly(74) *Attorney, Agent, or Firm* — Banner & Witcoff, Ltd.(57) **CLAIM**

The ornamental design for a portable electric driver, as shown and described.

DESCRIPTION

FIG. 1 is a front, left-side, and top perspective view of the portable electric driver showing our new design;

FIG. 2 is a rear, right-side, and top perspective view thereof;

FIG. 3 is a front elevation view thereof;

FIG. 4 is a rear elevation view thereof;

FIG. 5 is a left-side elevation view thereof;

FIG. 6 is a right-side elevation view thereof;

FIG. 7 is a top plan view thereof; and,

FIG. 8 is a bottom plan view thereof.
